UNITED STATES PATENT OFFICE.

GEORGE H. FORSYTH, OF CHICAGO, ILLINOIS.

DISK WHEEL.

Application filed July 11, 1921. Serial No. 484,009.

To all whom it may concern:

Be it known that I, GEORGE H. FORSYTH, a citizen of the United States, residing at Chicago, in the county of Cook and State of Illinois, have invented certain new and useful Improvements in Disk Wheels, of which the following is a specification.

The present invention relates to disk wheels, wherein the disk forming the body of the wheel and the laterally extending felly portion are one or both resiliently yieldable in the plane of the wheel and placed and maintained under diametrically applied reactionary stress by the rim or other constrictive peripheral member.

This application relates to subject matter carved out of my former applications which have matured into Patents Nos. 1,373,184 and 1,373,185, issued March 29, 1921, but is directed more particularly to that feature of the improvement in stressed disk wheels characterized by the assembly with the disk of a constrictive member independent of the demountable rim, which will retain the disk under uniform stress when the rim is removed.

In order that the invention may be readily understood I have in the accompanying drawings and in the following detailed description predicated thereon set forth preferred and alternative embodiments of the invention. As, obviously, the invention may be embodied in other forms differing in detail from those illustrated and described, it will be understood that the embodiment chosen by way of illustration and as a basis for the language used in the description are not to serve as unnecessarily limiting the invention defined in the claims.

In the drawings,

Fig. 1 is a fragmentary radial section through the peripheral portion of a wheel showing a constrictive band arranged about the marginal portion of an integral felly;

Fig. 2 is a similar view showing a constrictive band substantially co-extensive with the felly; and

Fig. 3 shows a constrictive band forming the felly of the wheel.

Having reference to Fig. 1 of the drawing, the disk body 11 of the wheel is shown as provided with a shoulder 12 near its periphery serving as a seating support for the rim-positioning and retaining clip member

13, the peripheral portion of the disk extending laterally at an angle to form a felly

14, both the felly and disk body being yieldable diametrically.

Normally the felly portion 14 of the wheel is of a diameter greater than the interior diameter of the demountable rim 15. In order to place and maintain the same under inwardly directed compressive stress the constrictive band 16 is assembled with the wheel by a lateral movement from the left to the right as shown in Fig. 1 until its beaded end 17 riding up upon the inclined face of the felly snaps over the marginal portion 18 thereof to prevent any backward movement. The outer circumference of the band 16 is substantially the same as the inner circumference of the rim 15 and forms a firm seat therefor as the rim is later assembled laterally therewith.

The rim being in place upon the wheel, a spring clip 13, which may be in the form of individual members or an annulus, is placed in position beneath and bearing upon the front face of the rim and drawn home by means of the nuts 19 on the bolts 20, the heads 21 of which bear upon the rear face of the disk.

To prevent disassociation of the bolts 20 from the wheel, they are, in the course of manufacture, after inserting in the apertures 24 of the disk, provided with spurs 22 which prevent their withdrawal from the rear. To hold them securely against turning, the shank of the bolt at 23 is squared and the aperture 24 of the disk is of corresponding configuration.

Having reference to Fig. 2 of the drawings, it will be observed that the dished disk 25 is illustrated provided with a rear radial rib 26, the peripheral portion of the disk being laterally extended to the rear at an inclination to form the felly portion 27 terminating at 28. The felly of the disk when made is of slightly greater diameter than in the position illustrated, and is placed under radially directed compressive stress by a constrictive band 29 having an upturned rear rim retaining portion 30 and an inner shoulder 31, as also an inwardly directed front flange 32. This constrictive band 29 is forced upon the disk laterally from the left as shown in Fig. 2, compressing the disk 25 and the felly 27 until it snaps over the edge of the felly at 28 which then forms an abutment for the shoulder 31 of the band. The band is so proportioned that at this time the flange 32 bears against the front face of the

disk, and the disk and felly are held at all times under stress. The demountable rim 33 is adapted for application to the wheel in the usual way by a lateral movement, a rim positioning and retaining clip 34 being employed, which clip has on its inner face a nose 35 which rides upon the band 29 to bear rearwardly and upwardly upon the rim. The clip is assembled with the disk and with 10 the band by means of a bolt 36 extending through apertures of each, and adjustable by means of the nuts 37, the squared edge of the bolt 38 being prevented from turning by its contiguous relation to the rib 26.

15 In Fig. 3 is shown a form of construction in which the forwardly dished disk 40 has no integral felly member associated therewith. The disk shown in this figure has its peripheral margin 41 snapped within the recess 42 upon the inner face of a constrictive band 43 which forms the felly of the wheel. The disk is placed under stress and as soon as it enters the recess 42 it maintains a firm seat but is held from resuming its former 20 diameter by the constrictive effect of the band 43. The strut member 44 is arranged at intervals about the wheel having its upper rear edge snapped within the recess and bearing against the shoulder 45 along the rear 25 margin of the felly member 43, while in its forward portion it is provided with a boss 46 seated within an aperture 47 of the wheel. The boss 46 is interiorly threaded for engagement with the bolt 48 which serves to 30 position and retain the rim positioning clip 49, the nose 50 of which rides upon the inclined surface 51 of the constrictive felly 43.

I claim:

1. In a wheel, the combination with a disk 40 body, a felly member, and a tire carrying 45 rim, of a peripheral constrictive member for maintaining the disk under radially applied compressive stress independently of the rim.

2. In a wheel, the combination with a disk 45 body of curved diametric cross-section, a felly member, and a tire carrying rim, of a separate peripheral constrictive member for maintaining the disk under radially applied compressive stress.

50 3. In a wheel, the combination with a disk body of reversely curved diametric cross-section, a felly member, and a tire carrying rim, of a peripheral constrictive member for maintaining the disk under radially applied compressive stress.

55 4. In a wheel, the combination with a disk body diametrically yieldable, a felly member, and a tire carrying rim, the disk having a slightly greater diameter when unstressed 60 than the interior diameter of the constrictive member whereby in assembled relation the constrictive member maintains the disk under inwardly directed radial stress.

65 5. In a wheel, the combination with a disk body diametrically yieldable and having an

obliquely disposed peripheral portion, a felly member, and a tire-carrying rim, having a constrictive band of slightly less diameter than the normal diameter of the peripheral portion of the disk when unstressed, whereby 70 in laterally-assembled relation said band maintains the disk under inwardly-directed radial stress.

6. In a single disk wheel, the combination with a steel disk body having an integral 75 laterally and obliquely extending rim-supporting portion, and a tire-carrying rim seated thereon, of a constrictive band assembled between the rim and rim-supporting portion and maintaining the latter portion 80 of the disk under radial compression.

7. In a vehicle wheel, the combination with hub and rim portions, of an intermediate steel disk body having an obliquely disposed peripheral portion of slightly greater diameter 85 when unstressed than the rim portion and underlying and supporting the same, and a constrictive band surrounding the peripheral portion of the wheel beneath the rim and maintaining the wheel under inwardly directed radial stress.

8. In a wheel, the combination with a disk body, an inwardly yielding felly or fixed rim portion, and a tire-carrying rim, of an encircling band adapted to be seated upon the yielding felly and to maintain the latter under inwardly-directed compressive stress.

9. In a wheel, the combination with a disk body, of a felly member, and a tire-carrying rim, the felly assembled with the disk body 100 in compressive relation to maintain the latter under stress, and strut members bearing upon the disk body and beneath the overhanging edge of the felly whereby to marginally support the latter.

10. In a wheel, the combination with a disk body, of a felly member, and a tire-carrying rim, of a rim positioning and retaining member, and bolts extending through the disk body and the tire retaining member from the rear and provided with adjusting nuts bearing upon the face of the tire retaining member, the shanks of the bolts upset against the face of the disk to prevent disassociation of the disk and bolts.

11. In a wheel, the combination with a radially yieldable disk body, of a peripheral constrictive member permanently assembled therewith for maintaining the same under radially applied compressive stress.

12. In a wheel, the combination with a disk body including a flanged felly member, of a peripheral constrictive member permanently assembled with the felly flange for maintaining the disk under radially applied compressive stress.

In testimony whereof I have hereunto signed my name.

GEORGE H. FORSYTH.
